PERCY GARDNER, OF EAST ORANGE, NEW JERSEY, ASSIGNOR TO H. M. BUNKER & CO., OF NEW YORK, N. Y., A CORPORATION OF NEW YORK.

CLOTH-ROLLING MACHINE.

Application filed February 8, 1927. Serial No. 166,775.

This invention relates to machines for winding the cloth into rolls, which rolls are subsequently sliced transversely to produce a number of narrow rolls of cloth tape, and 5 the machine is particularly designed for the winding of bias material.

In winding cloth into rolls for this purpose, it is positively essential to prevent the formation of wrinkles in the roll of cloth 10 for the reason that when the roll is sliced transversely the strips thus formed, if the cloth is wrinkled, will not present uniform widths.

It is therefore an object of the present 15 invention to provide a rolling machine which rolls the cloth smoothly and positively precludes the formation of wrinkles in the cloth when rolled.

In the machines of this character which 20 are now in general use and on the market, the cloth is rolled on a positively driven batching spindle and it is obvious that as the diameter of the roll increases, the speed at which the cloth feeds to the roll increases 25 to such an extent that even the highly skilled operators have difficulty in maintaining the edges of the outermost convolutions in substantial alinement. This results in considerable waste of material due to the 30 fact that the roll of cloth must have the ends where the edges of the convolutions are uneven, trimmed off before the remainder can be sliced. There is also ever present the possibility of wrinkling of the cloth 35 where the feed of the same becomes excessive.

It is therefore a further object of the present invention to provide an improved rolling machine of this character in which 40 the cloth is fed at a uniform rate of speed irrespective of the size of the roll being formed.

The invention furthermore comprehends a cloth rolling machine which specifically 45 includes a loosely mounted batching spindle upon which the cloth is rolled, with means engaging and exerting a frictional driving pressure upon the periphery of the cloth roll at substantially diametrically opposite 50 points, which means causes the cloth to be rolled by frictional driving pressure upon the periphery of the cloth roll, thereby causing the cloth to be fed upon the roll at a uniform rate of speed, which speed 55 admits of the operation of the machine with-

out constant attention so that a single operator may care for a plurality of machines.

The invention more specifically comprehends a loosely mounted batching spindle upon which the cloth is rolled, together with 60 a pair of positively driven drums or rollers engaging and exerting a pressure upon the cloth roll at diametrically opposite points of the periphery thereof and in which the cloth is trained around one of said drums 65 or rollers so that the accurate measurement of the yardage may be obtained by means of a counter coacting with said drums or rollers.

A further object of the invention resides 70 in the provision of a rolling machine which includes a loosely mounted batching spindle upon which the cloth is rolled and a pair of positively driven drums or rollers engaging or exerting a pressure upon the 75 cloth roll at diametrically opposite points of the periphery thereof, which drums or rollers exert a vise-like grip upon the cloth roll on the batching spindle to inherently prevent the formation of wrinkles in the roll 80 thus formed.

Other objects and advantages reside in the simplicity of construction, the economy with which the machine may be produced and operated, and the general efficiency derived therefrom.

With the above recited and other objects in view, reference is had to the following specification and accompanying drawings in which there is exhibited one example or 90 embodiment of the invention which is in no way intended as a limitation upon the scope of the appended claims as it is to be clearly understood that variations and modifications which properly fall within the 95 scope of said claims may be resorted to when found expedient.

In the drawings—

Figure 1 is a side view of a machine constructed in accordance with the invention; 100 Fig. 2 is a front view of the machine;

Fig. 3 is a fragmentary enlarged horizontal sectional view through the batching spindle and its bearings taken approximately on the line indicated at 3—3 in Fig. 2; 105

Fig. 4 is a fragmentary enlarged transverse sectional view taken approximately on the line 4—4 of Fig. 2.

Referring to the drawings by characters of reference, 10 designates the main frame 110

of the machine which is provided with bearing brackets 11 carrying bearings 12 and 13 in which alined stub shafts 14 and 15 are mounted. Either one or both of the stub shafts 5 may be axially movable in their bearings, but, as illustrated, the stub shaft 14 is rigid or immovable while the stub shaft 15 is axially movable or shiftable through the bearing 13. The stub shafts 14 and 15 carry on their inner ends respectively, journal bearings 16 and 17, having tapered or flared bores 18 for receiving the tapered or frusto-conical opposite extremities 19 of a batching spindle 20. As illustrated, the spindle is inserted in or removed from the journal bearings by shifting or moving the stub shaft 15 axially, and after the spindle is journaled the stub shaft is locked against outward shifting movement by a lock pin 21 inserted through the alined openings in the bearing 13 and stub shaft 15. It is obvious that this may be accomplished in any desired manner so that the batching spindle may be readily removed from or 25 mounted in the journal bearings. The batching spindle is adapted to receive thereon the usual tubular core C upon which the cloth or material M to be rolled is adapted to be wound. The main frame 10 has 30 mounted transversely therein for turning movement, a pair of superposed shafts 22 and 23, each of which has keyed thereto at one end, a pair of sprockets 24 and 25, and 26 and 27. A driving sprocket chain 28 is 35 trained around a driving sprocket 29 keyed or secured to a shaft 30 of a driving pulley 31 and around the sprocket 24 of the upper shaft 22, with one lead engaging the teeth of the sprocket 26 so that the sprockets 24 and 26 which are of the same ratio, are 40 driven in unison in the same direction and at the same rate of speed to turn the shafts 22 and 23 in the same direction and at the same rate of speed. The sprockets 25 and 27 are of the same ratio but are of less diameter than the sprockets 24 and 26. The 45 shafts 22 and 23 each have loosely mounted thereon for swinging movement, a pair of longitudinally spaced arms 32-32, and 50 33-33. The upper pair of arms 32 mounted on the upper shaft are connected by a connecting rod 34 at their forward ends, while the rear ends 35 are offset upwardly. The arms 33 of the lower shaft have their 55 rear extremities connected by a connecting rod 36. Between the shaft 22 which constitutes a fulcrum for the arms 32, and the connecting rod 34, a rotary shaft 37 is journaled or mounted for turning movement 60 and said shaft has keyed or otherwise secured thereto, a roller or drum 38 which is disposed between the arms. The shaft 37 has one of its ends extending beyond the arm and has keyed or otherwise secured 65 thereto, a sprocket 39 which is of the same ratio as the sprocket 25. A sprocket chain 40 is trained around the sprockets 25 and 39 for driving and turning the shaft 37 and roller or drum 38. The arms 33 have journaled or mounted for turning movement in 70 the forward ends, a shaft 41 which has keyed or otherwise secured thereto and positioned between the arms, a drum or roller 42, which drum or roller in the present instance is slightly less than twice the diameter of the drum or roller 38. The shaft 41 protrudes beyond one of the arms 33 and has keyed or otherwise secured thereto a sprocket 43 which is of a ratio with respect to the sprocket 27 to turn approximately 80 one-half the rate of speed of the sprocket 27 by virtue of a sprocket chain 44 which is trained around the sprockets 27 and 43. This arrangement turns the drum or roller 42 at slightly less than one-half the speed 85 of rotation of the drum or roller 38. The arms 32 and 33, their connecting rods 34 and 36 and the shafts 37 and 41, constitute a pair of frames for the rollers or drums 38 and 42, which are weighted to impinge or 90 grip the periphery of the cloth roll R on the batching spindle 20 at substantially diametrically opposite points to frictionally drive or turn the roll. If desired, additional or auxiliary weights 45 may be added 95 to the weighted frames by suspending the same from the connecting rods 36 or 34. Under this arrangement the cloth roll R on the batching spindle 20, is held in a vise-like grip between the peripheries of the two 100 driving rollers, or drums 38 and 42, which rollers, in effect, are tensioned against relative separation.

In view of the fact that the roller or drum 38 is slightly more than one-half the diameter of the roller or drum 42 and the latter is driven at approximately half the speed of the former, the peripheral driving speed of the roller 38 slightly exceeds the peripheral driving speed of the roller 42. This exerts 105 a constant tension on the outermost convolution of the cloth between the points of frictional driving engagement of the roller peripheries thereof and tends to positively 110 smooth and eliminate any wrinkle or unevenness in the cloth area.

The cloth is led or trained through a straightening frame 46 supported from the main frame 10 and which includes a plurality of rods 47 over and under which the cloth is alternately trained, adjustable guide plates 48 being employed in the usual manner to coact with the opposite side edges of the cloth strip. From the straightening frame the cloth is trained around a rear guide rod 49 and thence around the periphery of the roller or drum 42 and finally on to the cloth roll R. In view of the fact that the cloth is trained around the periphery 120 of the roller or drum 42 and travels at the 125 130

same peripheral speed as said roller or drum, it is obvious that an accurate measurement of the yardage may be obtained by associating a counter with the roll 42. It is further obvious for the reason that the cloth roll driving drums travel at a constant rate of speed, that the feed will be uniform from the beginning to the end of the rolling operation, thus eliminating the tendency of 10 the cloth to jam the guides 48 and produce wrinkles or unevenness in the edges of the cloth convolutions on the cloth roll R. This does away with the necessity of the constant service of an attendant so that one attendant 15 may operate a plurality of machines.

By offsetting the rear end of the arms 35 as illustrated, the upper frame carrying the roller or drum 38, may be swung to the position illustrated in dotted lines in Fig. 1, 20 so that the weight of the frame will be in rear of its fulcrum with the offset portions 35 engaging the shaft 23. This supports the frame in an opened condition to allow for the insertion or removal of the batching 25 spindle when starting the cloth roll or removing the same from the machine.

What is claimed is:

1. In a cloth rolling machine, a fixedly mounted freely rotatable batching spindle 30 upon which the cloth is rolled, and a pair of positively driven drums engaging and exerting a pressure upon the cloth roll at diametrically opposite points of the periphery for frictionally turning the same, the cloth being trained over the periphery of one of the 35 drums to permit of accurate measurement of the yardage.

2. In a cloth rolling machine, a fixedly mounted freely rotatable batching spindle 40 upon which the cloth is rolled, and a pair of positively driven drums engaging and exerting a pressure upon the cloth roll at diametrically opposite points of the periphery for frictionally turning the same, the cloth being trained over the periphery of one of the 45 drums, the other drum having a slightly greater peripheral speed for exerting a smoothing tension on the outer convolution of the cloth between the points 50 of engagement of the drums therewith.

3. In a cloth rolling machine, a fixedly mounted freely rotatable batching spindle upon which the cloth is rolled, and means 55 engaging and exerting a frictional driving pressure upon the periphery of the cloth roll at substantially diametrically opposite points, said latter means being relatively movable away from the batching spindle as the size of the cloth roll thereon increases.

4. In a cloth rolling machine, a fixedly mounted freely rotatable batching spindle upon which the cloth is rolled, a pair of frictional driving drums, and means for 65 mounting the same with respect to the

batching spindle to cause impingement of the peripheries thereof upon the cloth roll at diametrically opposite points of said cloth roll periphery, the mounting for said frictional driving drums allowing for 70 relative movement of the drums away from the batching spindle as the size of the roll increases.

5. In a cloth rolling machine, a fixedly mounted freely rotatable batching spindle 75 upon which the cloth is rolled, a pair of frictional driving drums, and means for mounting the same with respect to the batching spindle to cause impingement of the peripheries thereof upon the cloth roll at diametrically opposite points of said cloth roll periphery, said mounting means consisting of a weighted supporting arm for each drum.

6. A cloth rolling machine comprising a frame, a pair of superposed shafts mounted in the frame for rotation, a batching spindle upon which the cloth is rolled, mounted in the frame in advance of and upon an axis parallel to the superposed shafts and in a plane substantially midway between the 80 planes of said shafts, superposed frames fulcrumed on said superposed shafts, a drum rotatably carried by each frame, means for weighting the frames to effect a normal peripheral impingement of the drums with the 85 cloth roll on the batching spindle, means for driving the superposed shafts in the same direction and at the same rate of speed, and means for driving the drums from the shafts at approximately the same peripheral 90 speed whereby the cloth is frictionally wound upon the batching spindle.

7. A cloth rolling machine, comprising a frame, a pair of superposed shafts mounted in the frame, a batching spindle upon which the cloth is rolled, loosely mounted for turning movement in the frame, a frame fulcrumed on each of said shafts, a drum rotatably carried by each frame, means for effecting a normally peripheral impingement of 100 the drums with the cloth roll on the batching spindle, and means for driving the drums in the same direction at approximately the same peripheral speed, whereby the cloth is frictionally wound upon the 105 batching spindle.

8. A cloth rolling machine, including a frame, a batching spindle fixedly mounted in the frame for free turning movement and upon which the cloth is adapted to be rolled, 120 a pair of frictional driving drums carried by the frame and normally moved in a direction to peripherally engage the batching spindle at substantially diametrically opposite points, and means for rotating the drums 125 in the same direction and at substantially the same peripheral speed.

9. In a cloth rolling machine, a fixedly mounted freely rotatable batching spindle upon which the cloth is rolled, and a pair 130

of positively driven drums engaging and exerting a pressure upon the cloth roll at diametrically opposite points of the periphery for frictionally turning the same.

- 5 10. In a cloth rolling machine, a fixedly mounted freely rotatable batching spindle upon which the cloth is rolled and with which cloth roll the spindle turns, and uniformly driven means engaging and exerting 10 a frictional driving pressure upon the periphery of the cloth roll at substantially diametrically opposite points whereby a uniform feeding of the cloth to the roll is obtained.
- 15 11. In a material rolling machine, a fixedly mounted freely rotatable batching spindle upon which the material is rolled, and relatively movable means for gripping therebetween and exerting a frictional driving 20 pressure upon the periphery of the material roll.

12. In a material rolling machine, a fixedly mounted freely rotatable batching

spindle upon which the material is rolled, and relatively movable means for gripping therebetween and exerting a frictional driving pressure upon the periphery of the material roll at substantially diametrically opposite points.

13. In a material rolling machine, a 30 fixedly mounted freely rotatable batching spindle upon which the material is rolled, and means gripping therebetween and exerting a frictional driving pressure upon the periphery of the material roll at substantially 35 diametrically opposite points.

14. In a material rolling machine, a fixedly positioned freely rotatable batching spindle upon which the material is rolled, and relatively movable oppositely driven 40 rollers gripping therebetween and exerting a frictional driving pressure upon the periphery of the material roll at substantially diametrically opposite points.

PERCY GARDNER.
